UNITED STATES PATENT OFFICE.

FRED S. CARR, OF NEWTON, MASSACHUSETTS, ASSIGNOR TO CARR FASTENER COMPANY, OF CAMBRIDGE, MASSACHUSETTS, A CORPORATION OF MAINE.

FASTENER.

Application filed January 22, 1924. Serial No. 687,753.

To all whom it may concern:

Be it known that I, FRED S. CARR, a citizen of the United States, and resident of Newton, in the county of Middlesex, State of Massachusetts, have invented an Improvement in Fasteners, of which the following description, in connection with the accompanying drawings, is a specification, like characters on the drawings representing like parts.

10 This invention aims to provide an improved separable fastener, particularly though not exclusively useful for securing carpets and the like to floors.

15 In the drawings, which illustrate a preferred form of my invention:—

Figure 1 is a plan view of one corner of a carpet;

20 Fig. 2 is a section on the line 2—2 of Fig. 1;

Fig. 3 is a top plan view of the socket;

Fig. 4 is a bottom plan view of the socket;

25 Fig. 5 is a section on the line 5—5 of Fig. 3; and

Fig. 6 is a section on the line 6—6 of Fig. 4.

Referring to the drawings, the preferred form of my invention illustrated shows the usual stud having a head 1, a neck 2, a base 30 portion 3, and a screw 4 to be secured to the floor 5 of an automobile or the like to hold the stud in the desired position.

The preferred form of socket is pressed from a single sheet of metal and has an outer cylindrical wall 6 presenting a plurality of upstanding attaching prongs 7, generally like those shown in my co-pending application Serial No. 687,752 filed herewith. A second and inner cylindrical wall 8 is provided to present a plurality of radially extending resilient fingers 9 having reversely bent neck-engaging portions 10 surrounding a stud-receiving aperture 11. The inner and outer cylindrical walls are connected at the bottom of the socket by a web 12. The resilient fingers 9 are connected at their outer ends to the inner cylindrical wall 8, and these fingers preferably curve downwardly from their points of attachment to the inner wall 8 to a low point about midway of the fingers and then curve upwardly again so that the reversely bent neck-engaging portions 10

will be located upon the same general plane as the outer ends of the fingers 9. Thus the resilient fingers are free to flex with attendant engagement of the stud-receiving aperture 11 to permit passage therethrough of the head 1 of the stud when said head is being engaged in or disengaged from the socket. The curve of the resilient fingers 60 greatly increases their strength and their very considerable length greatly decreases the amount which the metal adjacent their outer ends must flex during engagement and disengagement of the stud.

The socket is attached to the warp and weft threads of the carpet and the prongs are concealed by the pile of the carpet in much the same manner as described in my co-pending application above referred to.

70 The prongs, extending outwardly from the casing, do not interfere with free upward movement of the stud-engaging fingers during the entrance of the stud into the socket, and do not hold the carpet backing 75 so closely and firmly against the top of the socket as to interfere with this movement of the fingers, as would be likely to be the case were the prongs thrown inwardly instead of outwardly.

80 When the socket is engaged with the stud, the web 12 is seated against the floor 5 of the automobile, and the space provided between the floor 5 and the resilient prongs 9 proves a convenient recess for the base 85 3 of the stud, thus doing away with the countersinking of the base of the stud into the floor, as is desirable with known types of sockets. The inner and outer cylindrical walls provide a very rigid and 90 substantial support for the attaching prongs 7 and for the resilient fingers 9, while they prevent possible crushing of the casing or damage to the resilient fingers when the carpet is stepped on directly over the fastener.

95 The socket may be separated from the stud by an upward pull upon the carpet, separation being relatively easily effected because the outer portions of the resilient fingers, about which they flex, are generally 100 in the same plane as the neck-engaging portions 10.

If the plane of the outer portions of the fingers were substantially above the general

plane of the neck-engaging portions 10, the entrance of the stud into the socket would be difficult, and the life of the socket short, because the stud-receiving aperture would initially contract when pressed against the head of the stud. Conversely, if the plane of the outer portion of the fingers were substantially below the general plane of the neck-engaging portions 10, the disengagement of the stud from the socket would be difficult, and the life of the socket short, because the walls of the stud-engaging aperture would tend to contract and more tightly grip the head of the stud when disengaging strain was applied. By locating the outer portions of the fingers in substantially the same plane as the stud-engaging portions 10, which constitute the wall of the stud-receiving aperture, any movement of the inner ends of the fingers, either above or below this plane, increases the area of the stud-receiving aperture with resultant ease in both the engaging and disengaging operations.

25 While I have shown and described a preferred form of one embodiment of my invention, it will be understood that changes involving omission, substitution, alteration and reversal of parts, and even changes in the mode of operation, may be made without departing from the scope of my invention, which is best defined in the following claims.

Claims.

35 1. A carpet fastener socket comprising a casing presenting an outer cylindrical wall, an inner cylindrical wall, a web connecting said outer and inner walls, a plurality of stud-engaging fingers surrounding a stud-receiving aperture, and a plurality of attaching prongs extending upwardly from said outer cylindrical wall.

2. A carpet fastener socket comprising a casing including an upstanding annular wall, a plurality of resilient stud-engaging fingers extending inwardly from the upper periphery of said wall, and a plurality of attaching prongs extending upwardly from the periphery of said casing.

50 3. A carpet fastener socket comprising a casing presenting an annular wall, a plurality of resilient stud-engaging fingers extending inwardly from said wall, and reversely bent neck-engaging portions located at the inner ends of said fingers and providing a peripheral wall surrounding a stud-receiving aperture, the outer ends of said fingers and the neck-engaging portions thereof located substantially in the same horizontal plane, thereby permitting expansion of said stud-receiving aperture by pressure exerted upon said fingers either in an upward or downward direction.

60 4. A carpet fastener socket comprising a one-piece casing including inner and outer

annular parallel walls, a web connecting said parallel walls, the bottom of said web providing the supporting surface of said socket, and a plurality of resilient fingers extending inwardly from the upper periphery of the inner wall.

5. A carpet fastener socket presenting a plurality of resilient fingers surrounding a stud-receiving aperture, an inner cylindrical wall supporting said resilient fingers, an outer cylindrical wall surrounding said inner cylindrical wall and a web connecting the bottoms of said cylindrical walls.

6. A one-piece socket for carpets and the like comprising an outer cylindrical wall, an inner cylindrical wall, a plurality of inwardly extending spring fingers connected at their outer ends to said inner cylindrical wall, said fingers forming a stud-receiving aperture in said socket, and a connecting web between said cylindrical walls.

7. A one-piece socket for carpets and the like comprising an outer cylindrical wall, an inner cylindrical wall presenting a plurality of inwardly projecting spring fingers, said fingers having at their inner ends reversely bent edges constituting the wall of a stud-receiving aperture and a connecting portion between the bottoms of said cylindrical walls.

8. A socket for carpets and the like formed from a single sheet of metal and comprising a cylindrical wall presenting a plurality of inwardly extending stud-engaging fingers, said fingers resiliently displaceable either upwardly or downwardly and disposed to enlarge the stud-receiving aperture on either upward or downward displacement thereof, and a second cylindrical wall surrounding said first cylindrical wall and connected thereto.

9. A carpet fastener socket comprising a one-piece casing including a cylindrical wall, and a plurality of resilient fingers extending inwardly from the upper part of said wall, said fingers curved slightly downwardly from said wall, then upwardly and terminating about the periphery of a stud-receiving aperture, said inner ends lying in the same general plane as the top of said wall to permit equal flexing of said fingers above or below said plane, when the head of a stud is entered or withdrawn from said stud-receiving aperture.

10. A carpet fastener socket presenting a plurality of peripheral prongs adapted to pierce the back of the carpet, a supporting base adapted to rest on the floor about the base of a stud and a plurality of spring stud-engaging fingers connected to the base substantially above the bottom thereof and arranged to flex either upwardly or downwardly to enlarge the stud-engaging aperture.

11. A carpet fastener socket comprising a

ring-like body of metal having projecting from one face thereof attaching prongs adapted to pierce the carpet web and be bent outwardly over the same in the pile and presenting its opposed face for contact with a support beneath the carpet, the metal continuing from said latter face in undulations or folds disposed between the two faces of

10 said body and defining a stud-receiving opening, said undulated or folded portion being split adjacent said opening to provide yielding stud-engaging jaws.

In testimony whereof, I have signed my name to this specification.

FRED S. CARR.
